UNITED STATES PATENT OFFICE.

EDWARD W. CONRADI, OF SEATTLE, WASHINGTON.

BLANK-FEEDING MECHANISM.

1,278,438.

Specification of Letters Patent. Patented Sept. 10, 1918.

Application filed February 25, 1914. Serial No. 820,882.

To all whom it may concern:

Be it known that I, EDWARD W. CONRADI, a citizen of the United States, residing at Seattle, in the county of King and State of Washington, have invented certain new and useful Improvements in Blank-Feeding Mechanism, of which the following is a specification.

My invention relates to improvements in machines for forming can-bodies and particularly to improvements in the type of machine shown and described in my Patent No. 1,129,456.

The object of the invention is the provision of a machine which will be readily adjustable in transverse directions to accommodate various lengths of can-body blanks, and particularly to provide for the lateral adjustment of the vertical walls of the side-rails of the machine and of the side-walls of the hopper coincidentally at one operation.

Another object of the invention is the provision of laterally adjustable supporting members for the pile of can-blanks whereby the space between said members may be suitably proportioned in accordance with the distance between the side-walls of the hopper and the length of the can-blanks; and to predeterminedly provide for the desired amount of sagging or deflection from the normal horizontal plane of the blanks.

A still further object of the invention is the provision of adjustably inclined side-walls adapted to engage the lateral extremities of the blanks at the bottom of said pile whereby the lowermost blanks are more or less bowed and separated and may be singly removed by the operative devices provided therefor. Other objects of the invention will be apparent in the further description of the invention.

The invention consists in the novel construction, adaptation and combination of parts of a can-body forming machine, which is fully described in the following specification, such parts thereof as are necessary to the understanding of my invention being illustrated in the accompanying drawings, and finally set forth in the appended claims.

In said drawings, Figure 1 is a top plan view of the feed-end portion of a can-body forming machine embodying my invention. Fig. 2 is an enlarged vertical, longitudinal, sectional view of a portion thereof taken upon line 2-2 of Fig. 1. Fig. 3 is a vertical

transverse sectional view taken upon line 3-3 of Fig. 1, a plurality of sheets being illustrated in side elevation within the hopper. Figs. 4, 5 and 6 are detached perspective views of details of the invention.

Referring to said views, the reference numeral 5 indicates the framework of a can-body forming machine supported upon legs 6 and provided with bed-plate 7 rigidly mounted in vertical alinement with the longitudinal axis of said frame. Horizontal side-rails 8 and 8¹ upon opposite sides of said bed-plate are formed with vertically disposed flanges 9 and 9¹, respectively, affording guides for the movements of the blanks upon said bed-plate, and upon which the various can-body forming devices, not shown, for working upon the blanks as they successively advance thereto, are mounted. Said side-plates are adjustable in lateral directions to and away from each other and said bed-plate to accommodate various lengths of can-blanks. Adjustment of said side-plates may be made by means of feed-screw 10 having oppositely disposed screw-threads upon its opposite ends engageable in threaded nuts 11 and 11¹ dependent upon the respective side-plates.

Said feed-screw is rotatably mounted in a fixed portion of the frame, as at 12, and is manipulated through hand-wheel 13. Said side-rails may obviously be adjusted individually but the method described is preferable, as said elements are thus at all times disposed symmetrically with relation to said bed-plate.

Said rails are formed with longitudinal parallel grooves 15 in which the reciprocating feed-bars 16 are slidably mounted and actuated as hereinafter fully set forth and as also described in my said patent.

Feed members 17 are adjustably mounted by set screws 17¹ upon said feed-bars for movement laterally thereof whereby the projections 18 are disposed more or less toward the median line between said feed-bars in position to engage the rear edges of the blanks.

At the feed end of the machine a hopper 10⁵ is provided having side-walls consisting of continuations of the side flanges 9 and 9¹ and which are adjustable laterally therewith. Front walls of said hopper are formed by angle-plates 19 and 19¹ adjustably secured by set bolts 18¹ to the respective side flanges 9, 9¹ to accommodate the various

widths of blanks. A cross-piece 20 is slidably secured to said angle-plates to allow of transverse movement of the latter with the side-rails 8, 8¹ to which is medially secured 5 the arm 21 adjustable vertically thereto to extend downwardly to the bottom of the pile of blanks B wherefrom the lowermost blank to be removed from the pile must be deflected downwardly, as will presently 10 be described, in order to be fed from the hopper.

The rear walls 22 for said hopper are also adjustable at 23 longitudinally of the machine to insure that the suction device 25 will 15 approximate a central position relative to the hopper-walls.

The said suction device 25 is reciprocatively movable in vertical directions and is mounted upon the machine framework, 20 and is formed with an axial bore 43 open at its upper end 44. A flexible hose 40 connects the said bore 43 with an air suction pump 26. The power driven shaft 42 is arranged to actuate the said feed bars 16 through a disk 25 crank 45 operatively connected to a cross head 46 of the feed bars by means of a connecting rod 47. At each revolution of said crank disk, the said suction member 25 is elevated during the contact of a pin 48 projecting from the said disk with an integral lug 49 upon and partially surrounding the said suction member 25, the reverse descending stroke of said member 25 being accomplished through the force of gravity. The air 30 pump 26 is likewise operatively connected to a crank 50 of the shaft 42 and is arranged to have its suction stroke whereby the air is partially exhausted in its cylinder, and in the bore 43 just before the member 25 reaches the culmination of its upstroke, and 35 during the major portion of its downstroke, and thus being so timed that the suction will occur in said device as it contacts with the lowermost of the pile of blanks contained in 40 said hopper.

Plates 27 for supporting said pile of blanks are mounted upon the respective side rails within the hopper and are provided with slots 28 wherein they may be adjusted 50 transversely of the hopper by bolts 30. Said plates are each provided at their inner extremity with a ledge 31 for supporting the blanks at points spaced inwardly from their side edges, whereby the pile of blanks as a 55 whole may be maintained in relatively horizontal condition.

Secured to said opposite side-walls of the hopper in proximity of their upper ends, as by bolts 32, are end-supporting clips 33 formed of a resilient metal sheet slotted at 34 for adjustment vertically by said bolts, and with an interiorly protruding lateral flange 35 at its lower end adapted to engage upon the underside of the lowermost of the 65 pile of blanks. An adjustment screw 36 is

mounted in the respective side-walls adapted to impinge upon the outer side of the lower end of said clip and spring the same laterally inward in an inclined direction toward said median line of the machine. The 70 office of said clips is to prevent the undue bowing upward of the middle portion of the pile of blanks under the influence of the upward stroke of said suction device by the weight of the pile of blanks being partially 75 or wholly transferred from said ledges 31 to said flanges 35 according to the amount of vertical movement upwardly of the middle of said pile. The inclined relation of the clips causes the lower blanks in the pile to 80 be more or less buckled downwardly in their middle portion and to become individually separated under the weight of the blanks thereabove whereby the suction device may readily displace the lowermost blank at each 85 of its downward reciprocal movements into the plane of engagement of said projections 18, as will be readily understood.

Having described my invention, what I claim, is—

1. In a machine of the class described, a hopper comprising means for supporting a stack of sheets of metal at the end portions of the sheets, said sheets being unsupported between their end portions, said hopper having inclined side parts, against which the ends of the sheets are adapted to contact as the sheets move downwardly in the hopper.

2. In a machine of the class described, a hopper comprising means for supporting a stack of sheets of metal at the end portions of the sheets, said sheets being unsupported between their end portions, said hopper having inclined side parts, against which the ends of the sheets are adapted to contact as the sheets move downwardly in the hopper, and means for adjusting the inclination of said inclined side parts.

3. In a machine of the class described, a hopper for holding a pile of sheets, means within the hopper for supporting the sheets at points spaced inwardly of the side ends of the sheets, and vertically adjustable and supplementary means at the sides of said hopper for supporting the side ends of said sheets.

4. In a machine of the class described, a hopper comprising means for supporting a stack of sheets of metal at the end portions of the sheets, said sheets being unsupported between their end portions, said hopper having inclined side parts, against which the ends of the sheets are adapted to contact as the sheets move downwardly in the hopper, means adapted to bend downwardly the middle portion of the sheet, and means adapted to engage the downwardly bent portion of the sheet and feed the sheet from the hopper.

5. In a machine of the class described, a hopper comprising means for supporting a

stack of sheets of metal at the end portions of the sheets, said sheets being unsupported between their end portions, said hopper having inclined side parts, against which the 5 ends of the sheets are adapted to contact as the sheets move downwardly in the hopper, suction means adapted to bend downwardly the middle portion of the sheet, and means adapted to engage the downwardly bent portion 10 of the sheet and feed the sheet from the hopper.

6. A machine of the character described, comprising a hopper, means for supporting

the sheets at the end portions thereof, said sheets being unsupported between their end portions, means for forcing the lower sheets 15 inward from their edges to bow and partially separate the sheets, and means for separating the lowermost sheet from the hopper.

Signed at Seattle, Wash., this 13th day of February, 1914.

EDWARD W. CONRADI.
